UNITED STATES PATENT OFFICE

ANDREW C. WOOD, OF CHICAGO, ILLINOIS

FLUID PUMP

Application filed September 13, 1930. Serial No. 481,664.

This invention relates to fluid pumps and particularly to that class of pumps wherein the operation of the pump is controlled by the quantity of fluid passing therethrough.

The present invention is particularly adaptable for use in connection with devices requiring varying quantities of fluid for their operation, as, for example, internal combustion engines, in the operation of which, varying quantities of fuel per minute pass through the carburetor, depending upon the speed or power delivered by the engine.

One object of the present invention is to provide a novel construction and arrangement whereby a predetermined maximum quantity of fluid in the reservoir of the pump will serve to actuate suitable mechanism for disconnecting the pump piston from its actuating member or rod.

Another object of the invention is to provide novel means for connecting the pump piston and actuating rod when the fluid in the reservoir of the pump is below a predetermined minimum level, the said connecting means being operable to disconnect the piston and rod when the predetermined maximum level is obtained.

Another object of the invention is to provide a novel construction and arrangement for maintaining the various elements of the connecting mechanism and the actuating means therefor in proper relative position with respect to each other.

A further object of the invention is to provide a novel construction and arrangement of check valves for controlling the flow of fluid pumped into the reservoir.

A still further object of the present invention is to improve devices of the character disclosed in sundry details hereinafter described and more particularly pointed out in the appended claims.

One embodiment of the present invention is shown for illustrative purposes in the accompanying drawing in which

Fig. 1 is a vertical sectional elevation of a pump or fluid elevating device embodying features of the present invention;

Fig. 2 is a sectional plan view of the struc-

ture shown in Fig. 1 and taken as indicated by the line 2—2 thereof;

Fig. 3 is a perspective view of the piston actuating member or rod employed in the illustrative embodiment; and

Fig. 4 is a perspective view of a collar or spring engaging washer adapted to be positioned on the actuating rod.

The illustrative embodiment of the present invention comprises a casing 5 having 60 preferably cylindrical side walls 6, base 7, and cover or top 8 secured to the side walls by means of cap screws 9, the base 7 having an inlet port 11 and outlet port 12 formed therein, the port 11 being provided with a suitable fitting 13 adapted to be connected to a suitable source of fluid supply, while the outlet port 12 is provided with a fitting 14 by which the pump may be connected with any suitable device designed for the use or 70 consumption of fluid as, for example, an internal combustion engine, and in connection with which the present invention will be described as to its operation.

The inlet port 11 is provided with a check valve shown, in the present instance, as comprising a flat plat 15 adapted to engage a valve seat 16 and pivotally connected to one end of an arm 17, which in turn is pivotally mounted on a bracket 18 carried by the base 7. 75

Also mounted on the base 7 within the casing 5, and preferably spaced from the walls 6 thereof, is a pump cylinder 19 surrounding the intake port 11 and having upwardly extending guides 21 associated therewith and positioned diametrically opposite each other, the said guides extending upwardly to a point adjacent the upper end of the casing.

Slidably mounted in the cylinder 19 is a piston 22 having a port or passage 23 formed therein, the said passage being provided with a check valve similar in construction to the valve 15 associated with the inlet port 11 and comprising a plate 24 pivotally connected to one end of an arm 25, which in turn is pivotally mounted on a bracket 26 carried by a portion of the piston.

Mounted on the piston 22 and preferably pivoted thereto is a yoke 27 formed of suit-

able material bent upon itself in a manner to form a bight portion 28 and downwardly extending substantially parallel leg portions 29, the lower ends of which are apertured to receive a pivot pin 31 mounted in upwardly extending ears 32 formed substantially diametrically opposite each other on the piston 22.

For reciprocating the piston 22 within the cylinder 19, a piston actuating member or rod 33 is slidably mounted in the casing, preferably through the use of a stuffing box 34 suitably positioned in the cover or top plate 8 of the casing, the upper end of the member 33 being pivotally connected at 35 to an arm 36 intermediate its end portions. The arm 36 is pivotally connected at 37 adjacent one of its end portions to the upper end of a link 38, the lower end of which is pivotally mounted on a bracket 39 carried by the top plate 8 of the casing.

The opposite or free end of the arm 36, in the present instance, is provided with an aperture 41 by which the arm may be connected to any suitable continuously operated driving mechanism for oscillating the arm and reciprocating the piston actuating member 33 in the stuffing box 34.

The piston actuating member 33 is shown in Fig. 3 of the drawing, and, in the present structure, comprises a rod having its upper portion of cylindrical form provided adjacent its upper end with a slot 42 adapted to receive the arm 36 while the lower end of the member or rod is flattened or cut away as indicated at 43 in a manner to form shoulders 44 at opposite sides of the flattened portion. The extreme lower end of the portion 43 is cut away or notched on its opposite edges as indicated at 45 in a manner to form a head 46 at its lower end, the flattened or reduced portion 43 of the piston actuating member 33 being adapted to be slidably positioned in a correspondingly formed aperture 47 formed in the bight portion 28 of the yoke 27 in a manner to maintain the yoke in a substantially vertical position on its pivot rod 31.

For operatively connecting the piston 22 and yoke 27 to the piston actuating member 33, a plurality of levers 48 are pivotally mounted at 49 on the yoke 27 between the leg portions 29 thereof and are provided at one side of their pivotal connection with downwardly and inwardly extending pawl-like portions 51 adjacent their lower ends adapted for engagement with the head 46, while at the opposite side of their pivotal connections, the levers 48 are provided with upwardly and outwardly extending portions 52 which serve, by reason of their position and weight, to yieldingly urge the pawl-like portions 51 toward the notched portions 45 of the member 33 and into the path of movement of the head 46 in a manner to be engaged thereby for moving the piston 22 in

an upward direction when the member 33 is moved upwardly. For moving the piston 22 and yoke 27 in the opposite or downwardly direction, a collar (Figs. 1 and 4) is provided with an elongated aperture 54 adapted to receive the flattened portion 43 of the member 33 in a manner to permit the positioning of the collar against the shoulders 44 formed on the member 33, and surrounding the portion 43 and positioned between the collar 53 and bight portion 28 of the yoke 27 is a helically coiled spring 55 sufficiently strong to overcome the weight of the check valve plate 24 and arm 25 and the pressure of the fluid beneath the piston when the piston is moved in a downward direction.

It will be noted from the foregoing description that a novel operative connection may be automatically established between the piston 22 and the piston actuating member 33, and through which the piston may be reciprocated by suitable driving means operatively connected with the arm 36, in a manner to draw fluid through the inlet port 11 until a sufficient quantity has been obtained to overflow at the upper edge 56 of the cylinder 19 into the space or channel formed between the cylinder and the walls 6 of the casing, and thence through the outlet port 12 and fitting 14 to a device where the fluid is employed or consumed as, for example, to an internal combustion engine employing liquid fuel for its operation.

For controlling the effective operation of the piston by the quantity of fuel contained in the casing 5, a float 57 is provided and shown in the present instance as comprising a plurality of sections 58 and 59 (see Fig. 2) positioned on opposite sides of the yoke 27 and the guides 21, by which the sections 58 and 59 are maintained in spaced relation with respect to the yoke 27.

The float sections 58 and 59 may be formed of any suitable material such as cork, or the like, and connected together at opposite edges of the yoke 27 by means of rods 61 so spaced and positioned with respect to the yoke that as the float rises within the casing 5, the rods will engage the portions 52 of the levers 48 in a manner to rock them about their pivotal connections 49, as indicated by dotted lines in Fig. 1, thereby withdrawing the pawl-like portions 51 of the levers out of the notches 45 and out of the path of movement of the head 46, which will permit the continued reciprocation of the piston actuating member 33 in its mounting without in any way affecting the position of the piston 22.

It will be noted that in the present instance, the guides 21 prevent any material amount of rotary movement of the float 57 thereby maintaining the rods 61 in position to properly engage the portions 52 of the levers 48 for effecting the release of the portions 51 from engagement with the head 46.

It will be noted also that when the piston 22 is in its lowermost position, as shown in Fig. 1, the spring 55 is compressed and a slight clearance obtains between the head 46 and pawl-like portions 51 to provide ample clearance of the portions 51 to effect their free release from engagement with the head when the levers 48 are rocked about their pivotal connections with the yoke 27 when the portions 52 of the levers are engaged by the rods 61.

Considering the present invention as used in conjunction with an internal combustion engine for supplying fuel to the float chamber associated with the carburetor thereof, the operation of the illustrative device is substantially as follows: With the elements in the position shown in full lines in Fig. 1 of the drawing, the oscillation of the arm 36 and reciprocation of the member 33 will cause the piston 22 to be reciprocated and on its upward movement to draw fuel through the intake port 11 and past the check valve 15 into the cylinder beneath the piston 22, and on its downward movement, the valve 15 will close and the valve 24 in the piston will yield to permit the fuel to pass through the port 23 to the upper side of the piston where it will be retained by the closing of the valve 24 until sufficient quantity has been obtained to overflow the upper edge 56 of the cylinder 19 into the space between the cylinder and side walls 6 of the casing, from which it will flow through the outlet port 12, fitting 14 and thence to the float chamber associated with the carburetor of the engine. As the fuel accumulates within the casing 5 to an extent beyond the quantity required for the operation of the engine, the float 57 will rise until a predetermined level of the fuel in the housing has been reached, at which time the rods 61 will engage the portions 52 of the levers 48 in a manner to rock the levers 48 about their pivotal connections 49 as indicated in dotted lines in Fig. 1, thereby withdrawing the portions 51 from engagement with the head 46, and, in so doing, disconnect the piston from the actuating member 33 which may continue to reciprocate without in any way affecting the position of the piston.

When sufficient fuel has been withdrawn from the casing 5 to permit the float 57 to drop by gravity a sufficient distance to move the rods 61 out of engagement with the portions 52 of the levers 48, the weight of the portions 52 will serve to urge the pawl-like portions 51 of the levers 48 into the notches 45 and into the path of movement of the head 46 in a manner to be engaged thereby upon an upward movement of the piston actuating member 33; thus it will be observed that an operative connection is automatically established, after which the piston will resume its reciprocating movements in the manner above described until sufficient fuel has again accu-

mulated within the casing to cause the float to rise and the rods 61 to again engage the portions 52 of the levers 48.

It will be observed from the foregoing description that the present invention provides a novel construction and arrangement for pumping or elevating fluids, and wherein novel means are provided for controlling the operation of the pump according to the quantity of fluid in the reservoir or casing thereof, and that the present invention also provides a novel construction and arrangement for actuating and maintaining certain elements of the device in suitable and desirable operative position with respect to other elements thereof.

Obviously, the present invention is not limited to the precise construction and arrangement shown and described as the same may be variously modified. Moreover, all the features of the present invention need not be used conjointly as the same may be used to advantage in various different combinations and sub-combinations.

What I claim as new and desire to cover by Letters Patent is:

1. In a device of the class described, the combination of a casing having inlet and outlet ports, a pump cylinder positioned in said casing and spaced therefrom in a manner to form a reservoir, a reciprocating piston mounted in said cylinder, an actuating member slidably mounted in the casing and automatically connectible to said piston, a float, and float actuated means for positively disconnecting said member from the piston.

2. In a device of the class described, the combination of a casing having inlet and outlet ports, a pump cylinder positioned in said casing, a piston operatively related to said cylinder, a yoke pivotally mounted on said piston, a piston actuating member slidably mounted in said casing and movable with respect to said yoke, means pivotally mounted on the yoke for automatically engaging said member in a manner to operatively connect the member and yoke together when the fluid in the casing is below a predetermined level, a float, and means carried thereby for actuating said connecting means in a manner to positively disconnect said member and yoke when the fluid in said casing attains a predetermined level.

3. In a device of the class described, the combination of a casing having inlet and outlet ports, a check valve operatively related to said inlet port, a pump cylinder mounted in said casing and surrounding said valve and inlet port, a piston operatively related to said cylinder, a check valve in said piston, a yoke mounted on the piston, a piston actuating member slidably mounted in said casing and having a notch formed therein, a lever pivotally mounted on said yoke and movable into said notch, a float, and

means carried on said float and engageable with said lever for positively moving the lever out of said notch.

4. In a device of the class described, the combination of a casing having inlet and outlet ports, a check valve operatively related to said inlet port, a pump cylinder mounted in said casing and surrounding said valve and inlet port, a piston operatively related to said cylinder, a check valve in said piston, a yoke pivotally mounted on the piston, a piston actuating member slidably mounted in said casing and having notches formed therein at opposite sides thereof, a plurality of levers pivotally mounted on said yoke at opposite sides of said member and movable into said notches, a float, means carried by said float and engageable with said levers for moving the levers out of said notches, and means for guiding said float in a manner to maintain said lever engaging means in operative position with respect to said levers.

5. In a device of the class described, the combination of a casing having inlet and outlet ports, a pump cylinder mounted in said casing, a piston operatively related to said cylinder, a yoke mounted on said piston, a piston actuating member having a head formed thereon, a plurality of levers pivotally mounted on said yoke and engageable with said head for moving said piston in one direction, resilient means operatively related to said yoke and actuating member for moving said piston in the opposite direction, a float, and means carried thereby for engaging said levers in a manner to move the levers out of engagement with said head.

6. In a device of the class described, the combination of a casing having inlet and outlet ports, a pump cylinder mounted in said casing, a piston operatively related to said cylinder, a yoke mounted on said piston, a piston actuating member having a head formed thereon, a plurality of levers pivotally mounted on said yoke and engageable with said head for moving said piston in one direction, resilient means operatively related to said yoke and actuating member for moving said piston in the opposite direction and for permitting a downward movement of said member with respect to said piston in a manner to provide a clearance to facilitate the engagement and disengagement of said levers and head, a float, and means carried thereby for engaging said levers in a manner to move the levers out of engagement with said head.

7. In a device of the class described, the combination of a casing having inlet and outlet ports, a pump cylinder mounted in said casing, a piston operatively related to said cylinder, a yoke mounted on said piston, a piston actuating member having a shoulder and head formed thereon, a plu-

rality of levers pivotally mounted on said yoke and engageable with said head for moving said piston in one direction, resilient means operatively related to said yoke and shoulder for moving said piston in the opposite direction, a float, means carried thereby for engaging said levers in a manner to move the levers out of engagement with said head, and guides for maintaining said lever engaging means in operative position with respect to said levers.

8. In a device of the class described, the combination of a casing having inlet and outlet ports, a pump cylinder mounted in said casing, a piston operatively related to said cylinder, a yoke mounted on said piston, a piston actuating member having a head formed thereon, a plurality of levers pivotally mounted on said yoke and having pawl-like portions on one side of their pivotal centers engageable with said head for moving said piston in one direction and also portions extending outwardly from the pivotal centers adapted to move said pawl-like portions into the path of movement of said head, resilient means operatively related to said yoke and actuating member for moving said piston in the opposite direction, a float, and means carried thereby for engaging the outwardly extending portions of the levers in a manner to move the pawl-like portions thereof out of engagement with said head.

9. In a device of the class described, the combination of a casing having inlet and outlet ports, a pump cylinder mounted in said casing, a piston operatively related to said cylinder, a yoke mounted on said piston, a piston actuating member having a shoulder and a head formed thereon, a plurality of levers pivotally mounted on said yoke and having pawl-like portions on one side of their pivotal centers engageable with said head for moving said piston in one direction and also portions extending outwardly from the pivotal centers adapted to move said pawl-like portions into the path of movement of said head, resilient means operatively related to said yoke and shoulder for moving said piston in the opposite direction, a float, means carried thereby for connecting portions of the float together and engageable with the outwardly extending portions of the levers in a manner to move the pawl-like portions thereof out of engagement with said head, and guides extending upwardly between portions of said float for maintaining said lever engaging means in operative position with respect to the outwardly extending portions of said levers.

10. In a device of the class described, the combination of a casing having inlet and outlet ports, a pump cylinder mounted in said casing, a piston operatively related to said cylinder, a yoke mounted on said piston, a piston actuating member having a shoulder

and head formed thereon, a plurality of levers pivotally mounted on said yoke and having pawl-like portions adjacent their lower ends at one side of their pivotal centers and engageable with said head for moving said piston in one direction and also portions extending outwardly from the pivotal centers adapted to move said pawl-like portions into the path of movement of said head, resilient means operatively related to said yoke and shoulder for moving said piston in the opposite direction, a float having portions positioned on opposite sides of said yoke, means carried by said float for connecting said portions of the float together and engageable with the outwardly extending portions of the levers in a manner to move said pawl-like portions thereof out of engagement with said head, and guides extending upwardly between portions of said float for maintaining said lever engaging means in operative position with respect to the outwardly extending portions of the levers and for maintaining the float out of engagement with said yoke.

11. In a device of the class described, the combination of a casing having vertical side walls, a pump cylinder extending upwardly in said casing and spaced from the walls thereof, said casing having an inlet port positioned in said cylinder and an outlet port positioned between said cylinder and side walls, a check valve operatively related to said inlet port, a piston mounted in said cylinder, a check valve mounted in said piston, a yoke pivotally mounted on said piston, a piston actuating member slidably mounted in said casing and operatively related to said yoke in a manner to maintain the yoke in a substantially vertical position, a head and shoulder formed on said member, a plurality of levers pivotally mounted on said yoke and having downwardly extending pawl-like portions and outwardly extending portions adapted to move said pawl-like portions inwardly to engage said head for moving the piston in one direction, resilient means operatively related to said yoke and shoulder for moving said piston in the opposite direction, a float formed of a plurality of sections positioned respectively on opposite sides of said yoke, a plurality of rods connecting said float sections and adapted to engage the outwardly extending portions of said levers in a manner to move the pawl-like portions thereof out of engagement with said head, guide members extending upwardly from said cylinder between said float sections and engageable therewith for maintaining the sections in spaced relation with respect to the yoke and for maintaining said rods in operative position with respect to said levers.

In witness whereof I hereunto subscribe my name this 2nd day of September A. D., 1930.
